UNITED STATES PATENT OFFICE.

CHARLES P. POINIER, OF BOSTON, MASSACHUSETTS, ASSIGNOR TO F. A. HOWARD AND H. M. A. POOR, OF BELFAST, MAINE.

IMPROVEMENT IN MITERING-MACHINES.

Specification forming part of Letters Patent No. **159,552**, dated February 9, 1875; application filed June 10, 1874.

To all whom it may concern:

Be it known that I, CHARLES P. POINIER, of Boston, Massachusetts, have invented a Mitering-Machine, of which the following is a specification:

My invention relates to an improved adjustable rest for mitering-machines, its object being to prevent the article being mitered from canting backward during the operation; and consists of an adjustable rest connected by means of rods to two uprights attached to the rest of the mitering-machine. The uprights are provided with a series of holes one above the other, through which the connecting-rods pass, by means of which the connecting-rods and adjustable rest may be raised or lowered to the height required. The connecting-rods are held firmly in position by means of set-screws passing downward through the center of each upright, and intersecting the holes

through which the connecting-rods pass, the lower ends of the set-screws pressing upon the connecting-rods, and thus holding them in position.

In the accompanying drawing, *a a* represent the adjustable rest; *b b*, the connecting-rods; *c c*, the uprights; *d d*, the set-screws, and *e e* the rest proper of the mitering-machine.

I claim as my invention, and wish to secure by Letters Patent—

The combination of the adjustable rest *a*, provided with stems *b b*, with the uprights *c c*, having a series of holes, and the set-screws *d d*, substantially as and for the purpose described.

CHAS. P. POINIER.
